(57) **CLAIM**

The ornamental design for a faceted vase, as shown and described.

DESCRIPTION

FIG. 1 is a perspective view of a faceted vase according to the new design;

FIG. 2 is a front view of the faceted vase of FIG. 1, the rear view being a mirror image thereof.

FIG. 3 is a side view of the faceted vase of FIG. 1, the opposite side view being a mirror image thereof.

FIG. 4 is a top view of the faceted vase of FIG. 1.

FIG. 5 is a bottom view of the faceted vase of FIG. 1.

FIG. 6 is a perspective view of a faceted vase according to a second embodiment of the new design;

FIG. 7 is a front view of the faceted vase of FIG. 6, the rear view being a mirror image thereof.

FIG. 8 is a side view of the faceted vase of FIG. 6, the opposite side view being a mirror image thereof.

FIG. 9 is a top view of the faceted vase of FIG. 6; and,

FIG. 10 is a bottom view of the faceted vase of FIG. 6.
